UNITED STATES PATENT OFFICE.

CHARLES M. WEBB, OF WATERBURY, CONNECTICUT, ASSIGNOR TO WATERBURY BUCKLE CO., OF WATERBURY, CONNECTICUT, A CORPORATION.

RUSTLESS BUCKLE.

Application filed November 5, 1923. Serial No. 672,710.

To all whom it may concern:

Be it known that I, CHARLES M. WEBB, a citizen of the United States, residing at Waterbury, in the county of New Haven 5 and State of Connecticut, have invented a new and useful Improvement in Rustless Buckles; and I do hereby declare the following, when taken in connection with the accompanying drawings and the characters 10 of reference marked thereon, to be a full, clear, and exact description of the same, and which said drawings constitute part of this application, and represent in—

Fig. 1 a view in front elevation of a rust- 15 less buckle constructed in accordance with my invention, shown as applied to a piece of webbing.

Fig. 2 an edge view thereof.

Fig. 3 a sectional view on the line 3—3 of 20 Fig. 1.

Fig. 4 a view of the buckle-frame in front elevation on an enlarged scale.

Fig. 5 an edge view thereof.

My invention relates to an improvement 25 in rustless buckles of the type shown and described in United States Patent No. 847,811, granted March 19, 1907, on the application of Morris Peller, the object of my present invention being to produce a wire- 30 frame buckle in which the wire of the frame is bent to grip the fixed end of the webbing, whereby an economy of time, labor and web- 35 bing is effected, the sewing of the webbing to fasten it to the buckle being eliminated.

With these ends in view, my invention 40 consists in a wire-frame rustless buckle having certain details of construction as will be hereinafter described and pointed out in the claim.

As herein shown, I employ a buckle-frame made by bending a single piece of wire to form a continuous lower bar 6, the respective ends of which are bent downward, then inward, under the said bar, until they nearly 45 meet, and then downward and outward to form two complementary, web-gripping loops extending nearly to the center of the buckle, and respectively comprising upper reaches 7 and lower reaches 8, these loops 50 being located in the vertical plane of the lower bar 6, from which they are separated by a narrow, web-receiving opening 9. The

outer ends of the lower reaches 8 of the said loops are bent upward to form the side-bars 10 of the buckle-frame and then inward to 55 produce aligned pintle-ends 11, virtually forming the upper bar thereof. As shown, the side-bars 10 are bent forwardly at a point slightly above the lower bar 6, whereby the pintle-ends 11 are located in a plane 60 in front of the plane of the lower bar 6, and the web-gripping loops below the same. Upon the pintle-ends 11 I mount a standard, sheet-metal buckle-lever, having a finger-piece 12, a gripping-edge 13, and hinge- 65 fingers 14, which latter are wrapped around the pintle-ends, whereby the lever is pivotally mounted upon the same.

In webbing my improved buckle, what is to become the fixed end 15 of the web- 70 bing 16 is passed from front to rear, through the narrow opening 9 located between the lower bar 6 of the buckle-frame and the upper reaches 7 of the web-gripping loops thereof. The said bar and loops are now 75 subjected to edgewise pressure, whereby they are forced together, so as to measurably close the opening 9 and so firmly pinch the end 15 of the webbing and grip it between the bar 6 and reaches 7, as clearly shown in Fig. 3. The webbing is now passed from front to rear, over the lower bar 6 of the frame, through the webbing-opening 17 thereof, so as to form a cushioning-bend 18 in it, after which it is passed downward and 85 upward to form the ordinary loop and then from front to rear, over the bend 18 and through the said opening 17 and under the edge 13 of the buckle-lever, which is positioned to deflect the webbing from front to 90 rear, over the lower bar 6 of the buckle-frame and over the bend 18 of webbing, in the manner shown and described in the said Peller patent.

I claim:

A rustless buckle having a one-piece wire-frame bent to form a continuous lower bar, two web-gripping loops extending toward each other under the said lower bar in the vertical plane thereof and separated therefrom by a narrow web-receiving opening, two upstanding side-bars merging into the lower reaches of the said loops, and two pintle-ends bent inward from the upper ends 95 100 105

of the said side-bars; of a buckle-lever pivotally mounted upon the said pintle-ends in position to have its gripping-edge deflect the running portion of the webbing substantially over the said lower bar, the said opening being closed to grip the fixed end of the webbing.

In testimony whereof, I have signed this specification in the presence of two subscribing witnesses.

CHARLES M. WEBB.
